UNITED STATES PATENT OFFICE.

CHARLES H. KELLY, OF SPRINGDALE, FLORIDA.

MOISTURE-GAGE.

1,159,500.

Specification of Letters Patent.

Patented Nov. 9, 1915.

Application filed November 28, 1914. Serial No. 874,466.

To all whom it may concern:

Be it known that I, CHARLES H. KELLY, a citizen of the United States, residing at Springdale, in the county of Taylor and State of Florida, have invented new and useful Improvements in Moisture-Gages, of which the following is a specification.

This invention relates to moisture gages, and it has particular reference to a moisture 10 gage adapted to be used in connection with a lumber kiln.

In kilns for drying lumber it is necessary in order to obtain good results that a certain degree of moisture be permitted in 15 the drying room while the drying process is in progress. An insufficient degree of moisture causes the lumber to be surface dried, thereby closing the pores of the lumber and preventing the thorough drying of 20 the same without cracking or splitting, checking or warping.

In carrying out the operation of drying lumber in kilns it has been customary to remove at stated times a portion of the lumber which is supposed to have been thoroughly dried and introducing in the place thereof green lumber the evaporation from which is supposed to supply the necessary moisture. This does not always operate 25 satisfactorily, because the opening of the kiln permits the moist air to largely escape. Thus when the green lumber is introduced, a certain time will elapse before sufficient moisture is developed from evaporation 30 from such green lumber, and the partly dried lumber within the kiln is thus liable to be injuriously affected.

The present invention has for its object 40 to produce a gage whereby the amount of moisture in the drying room of the kiln may be correctly ascertained or made to appear at all times so that moisture may be removed from or supplied to the drying room, as conditions may require, thereby enabling 45 the drying operation to be carried out in the most successful and satisfactory manner.

A further object of the invention is to 50 produce a gage of simple and improved construction which will at all times visually indicate the state of humidity in the drying room with which it is connected, thus enabling measures to be quickly taken to correct any departure from the desired predetermined condition.

With these and other ends in view which will readily appear as the nature of the invention is better understood, the same consists in the improved construction and novel arrangement and combination of parts 60 which will be hereinafter fully described and particularly pointed out in the claims.

In the accompanying drawing has been illustrated a simple and preferred form of the invention, it being, however, understood 65 that no limitation is necessarily made to the precise structural details therein exhibited, but that changes, alterations and modifications within the scope of the claims may be resorted to when desired.

In the drawing, Figure 1 is a side elevation partly in section, showing the improved gage applied to the wall of a drying room. Fig. 2 is a horizontal sectional view taken on the line 2—2 in Fig. 1. Fig. 3 is a side 70 elevation partly in section, illustrating a modified construction of the improved device, and showing the same applied to the roof of a drying kiln.

Corresponding parts in the several figures 80 are denoted by like characters of reference.

Through the wall of the drying room which is indicated at 15 extends a pipe or duct 16, open at its inner end and connected at its outer end with the lower end of a 85 condensing chamber 17 which is preferably funnel-shaped at the bottom, and the upper part of which is surrounded by a water jacket 18 having inlet and outlet pipes 19, 20 to permit the circulation of a cooling 90 medium such as cold water. The top of the condensing chamber extends slightly above the water jacket and is provided with a valve 21 which, as shown, may be of the rotary cap type. Connected with the lower 95 funnel-shaped end of the condensing chamber is a gage glass 22 having at its lower end a pet cock 23 adapted to discharge into a vessel 24 supported on one end of a tilt-able beam or lever 25 fulcrumed on a support 26 and having at its other end an adjustable weight 27. The pipe or duct 16 is provided with a casing 28 having a door 29 which is preferably provided with a panel 30 of transparent material, such as glass, 100 for observation of a thermometer 31 within the casing.

The moisture laden air from within the drying room will escape through the pipe or duct 16, the temperature thereof being 110

indicated by the thermometer 31. As it reaches the condensing chamber 17 the moisture will be condensed by the action of the cooling medium, the water of condensation settling in the gage glass 22, while the partial vacuum created in the condensing chamber will induce a constant flow of moisture laden air from the drying chamber. The pet cock is to be set to permit the escape of the water of condensation as conditions, ascertained by experimentation, will warrant; it being understood that if condense-water escapes constantly at a predetermined rate, a constant level will be viewed in the gage glass and, furthermore, that when this level increases or decreases, it will indicate the need of changing the conditions in the drying room, either by permitting moisture laden air to escape through valves provided for the purpose or by supplying additional moisture in the form of steam or hot water. The state of the condense-water in the gage glass will thus at any time and at a glance indicate the condition of humidity in the kiln and enable measures to be taken for the correction thereof, if needed.

The cup supported on the tiltable lever 25 will serve to indicate the amount of water condensed in a given length of time, the cup being emptied at intervals by the tilting of the lever. This will serve as an indicator to assist in proper and correct adjustment of the pet cock.

In Fig. 3 of the drawings has been illustrated a somewhat modified form of the invention, and in this case the pipe or duct, here designated 16', which connects the condensing chamber 17 with the drying room, is shown as extending through the roof 15' instead of through the wall of the kiln, said duct 16' being in this case of angular shape.

When the gage glass 22 is connected directly with the lower end of the condensing chamber 17, as seen in Fig. 1, there is sometimes danger of said glass being completely emptied or else that the condense-water will accumulate above the sight limit, owing to the necessarily small capacity of the gage glass which, in order to clearly indicate variations, must be of small diameter and which also cannot be conveniently made of immoderate length. I have, therefore, in Fig. 3 shown an approximately U-shaped container C having a long limb 40 and a short limb 41, said long limb being flanged at its upper end, as seen at 42, and connected with a flange 43 at the lower end of the condensing chamber by means of bolts 44. Between the flanges 42 and 44 there is interposed a straining disk 46 which may be of felt or other sufficiently porous material. Supported on the short limb 41 of the container C and connected therewith by a gland 47 is a gage glass, which is here designated by 48. The pet cock, here designated by 23'

is connected with the container C. In other respects the construction is as herein previously described.

By the modified construction herein shown the volume of condense-water registering in the gage glass is materially increased, thereby increasing the efficiency of the device. By the modified construction I have also introduced the strainer 46 whereby pitch, rosin and other impurities contained in the condense-water will be intercepted and prevented from reaching the pet cock 23', thereby avoiding clogging the same which would interfere with the proper operation of the device.

In a drying room equipped with the improved moisture gage lumber will be dried more quickly and satisfactorily than in any other manner known to me. The drying room may be filled with green lumber, and the latter may be completely dried and cured without removing or changing any portion thereof until the drying operation is complete. It obviously becomes possible to regulate the humidity of the air with absolute accuracy, thereby permitting the lumber to dry evenly throughout, without being discolored by pitch drawn to the surface, without loosening the knots and without shipping, checking or warping. By the use of the present invention I have in practice succeeded in reducing time of drying by one-half, the resultant lumber being of a superior grade than has been obtained in kilns not provided with my improved moisture gage. The latter is simple in construction and easy of instalment and operation.

Having thus described the invention, what is claimed as new, is:

1. A moisture gage comprising a condensing chamber having at its lower end a gage glass to receive condense-water and at its upper end a valve, an inlet duct connected with the condensing chamber, said duct being equipped with a thermometer to indicate the temperature of the moisture laden air entering the condenser, a water jacket surrounding the condenser, and a pet cock to permit the discharge of water from the gage glass.

2. The combination with a drying room, of a device for visually indicating the degree of humidity in such drying room, the same consisting of a condenser communicating with the drying room to receive the moisture laden air therefrom, a U-shaped container having one limb connected with the condenser to receive the condense-water, a gage glass connected with the other limb of the container, and means for permitting the constant escape at a predetermined rate of water from the gage glass through the container.

3. The combination with a drying room, of a device for visually indicating the degree

of humidity in such drying room, the same consisting of a condenser communicating with the drying room to receive the moisture laden air therefrom, a U-shaped container 5 having one limb connected with the condenser to receive the condense-water, a gage glass connected with the other limb of the container, and a pet cock connected with the container to permit the constant escape of 10 water from the said container and the gage glass.

4. The combination with a drying room, of a device for visually indicating the degree of humidity in such drying room, the same

including a condenser communicating with 15 the drying room to receive the moisture laden air therefrom, a gage glass connected with the condenser, a strainer between the gage glass and the condenser, and a pet cock permitting the constant escape of water at 20 a predetermined rate.

In testimony whereof I affix my signature in presence of two witnesses.

CHARLES H. KELLY.
